Primary Examiner — John R Yeh

(57) **CLAIM**

The ornamental design for a window squeegee as shown and described.

DESCRIPTION

1. Window squeegee

1.1 : Top perspective view

1.2 : Bottom perspective view

1.3 : Front

1.4 : Back

1.5 : Left

1.6 : Top

1.7 : Bottom

The characteristic features of the design lie in the shape of the window squeegee as shown; possible use of the design: to remove water or any other liquid or solution from a flat surface; right side view is omitted because it is a mirror view of the left side view; the features shown by means of dashed lines form no part of the claimed design; the line shading in the drawings is a drawing convention to represent contours and does not illustrate surface ornamentation or decoration.
